Fig. 1

Fig. 2

Fig. 3

Fig. 4

FIGURE 1 is a bottom plan view of a fish lure showing my new design;

FIGURE 2 is an elevation of one side thereof, the other side being the same;

FIGURE 3 is a top plan view thereof;

FIGURE 4 is a front elevation and

FIGURE 5 is an end elevation.

The dominant features of my design reside in the portions shown in full lines, said portions being characterized by the specific configuration of the tail appendage in association with the lure body as shown.

I claim:

The ornamental design for a fish lure, as shown and described.
